CLAIM

The ornamental design for a photoelectric smoke detector, as shown and described.

DESCRIPTION

FIG. 1 is a left side elevational view of a photoelectric smoke detector showing our new design;

FIG. 2 is a top plan view thereof;

FIG. 3 is a right side elevational view thereof;

FIG. 4 is a side elevational view taken 90 degrees from FIG. 1;

FIG. 5 is a reduced bottom plan view thereof.

FIG. 1

FIG. 2

FIG. 3

FIG. 4

FIG. 5
